HEAT EXCHANGER

Application filed July 28, 1931. Serial No. 553,538.

- The present invention relates to heat exchangers and particularly to that type of exchanger in which one of the heat exchanging fluids is passed thru a long tube of fairly large diameter in which a smaller tube or a nest of smaller tubes is disposed, to provide passage for the other fluid, which may be either the heat container or the fluid to which heat is to be transmitted.
- 10 In existing heat exchangers of the type described, no provision is made for readily dissembling and cleaning the various parts of accumulated rust, scale and deposits left by the fluids passing therethru. In fact, 15 heat exchangers of the present type are welded so as to compose almost a unitary structure, which necessitates scrapping certain portions of the structure every time it is dissembled for cleaning, as such dissembling must be done by means of a cutting torch. It is needless to say that this procedure is both wasteful and expensive.
- Another objection to structures of the existing type is that no provision is made for 25 the stresses caused by the unequal expansion of the outside tube and the smaller tube or tubes therein. It is readily appreciable that such stresses must be set up, as the outer tube is approximately at the temperature of the 30 heat containing fluid, while the inner tubes are at the lower temperature of the fluid to which heat is being transferred, or the tube temperatures are just the reverse, depending on whether the heat containing fluid is passed thru the inner or outer tubes. However, this 35 phase of the invention can be dealt with to better advantage after a detailed description of the drawings.
- An object of the present invention is to 40 construct a heat exchanger which may readily be taken apart for cleaning or renewing corroded parts.
- Another object is to provide a structure with readily interchangeable parts so that 45 spare clean parts may be kept on hand and substituted for clogged or corroded parts with a minimum of time involved in the shutdown.
- Another object is to overcome the stresses 50 set up by unequal expansion of the fluid carrying tubes, and thereby prevent disrupting of any of the tubes due to such stresses and the loss caused by the necessary shut-down for repairs.
- A better understanding of the invention 55 may be had by reference to the accompanying drawings.
- Figure 1 is a longitudinal-sectional view of one section of my heat exchanger.
- Figure 2 is a diagrammatic view of four 60 sections of my heat exchanger connected in series.
- Figure 3 is a view of the movable tube sheet.
- Figure 4 is a view of an end connection for 65 the outer tube.
- Figure 5 is a view of the gasket retaining ring.
- Figure 6 is a view of the flexible gasket.
- In the drawings, 1 designates the external 70 tube of the heat exchanger having inlet and outlet ports 6, 6, respectively. To each end of this external tube is welded a flange designated 4, 4, respectively, each flange having bolt holes therein. Within the external tube 75 is a nest of smaller tubes, 3, which are longitudinally disposed with respect to the external tube. The ends of the smaller tubes are rolled into tube sheets 2 and 12 respectively. The tube sheet 12 is of the same diameter as 80 the flanges on the external tube, and is provided with bolt holes coinciding with the bolt holes in the flanges of the external tube. The tube sheet 2 (Fig. 3) is slightly smaller in diameter than the inside of the external 85 tube. There is provided a flexible gasket 10, (Fig. 6) which is detachably secured to the tube sheet 2 by means of a retaining ring 5, (Fig. 5) and bolts 7. At each end of each exchanger a pipe fitting 13 is provided. 90 These pipe fittings have flanges of the same diameter as the flanges of the external tube, and are also provided with bolt holes coinciding with the bolt holes in the flanges of the external tube.
- In assembling the exchanger, the smaller tubes, 3, are rolled into the tube sheets. The end of the nest having the smaller tube sheet therein is introduced into the external tube 95 and pushed through until the flange on the 100

larger tube sheet abuts the flange on the external tube. The bolt holes in these two flanges are then aligned. One of the pipe fittings is then lined up with the two previously mentioned flanges, the bolts are inserted and drawn home. A tight joint is made between the elements 4, 12, and 13 by means of the gaskets 11. The other end of the heat exchanger is then tightened up in the following manner. The flexible gasket 10 is secured between the flange of the external tube and the flange of the pipe fitting and the bolts drawn home. In order that the flexible gasket 10 will not have to carry the weight of one end of the tube nest, I weld a shim 16 to the inside of the external tube. This shim positions the tube sheet 2 concentrically with the external tube, the tube sheet 2 being free to slide back and forth upon the shim.

In practice several of the sections above described are connected in series as shown in Fig. 2 of the drawings. The fittings 13 are welded to return bends 14 as shown at 25 15 in Figs. 1 and 2. The inlets and outlets 6 are also welded as shown in Fig. 2.

In the operation of the described heat exchanger, if the external tube carries the heat containing fluid, this tube will be at a higher 30 temperature than the tubes 3, which are carrying the fluid to which heat is being transferred. As a natural consequence, the tube 1 will expand to a greater extent than the tubes 3. This expansion is taken up by the 35 corrugation in the gasket 10. If the process is reversed, and the small tubes 3 carry the heat containing the fluid, and the tube 1 the fluid to which heat is to be transferred, the tubes 3 will expand more than the tube 1. 40 Again this expansion will be taken up by the gasket 10. In case there is a greater relative expansion between the elements 1 and 3 than the elastic limit of the gasket 10 will permit, I have provided abutments 13a which 45 limit the expansion of tubes 3 or the contraction of tube 1.

If the gasket 10 were not provided, and this end of the exchanger were constructed as the other end, it is readily seen that any 50 relative contraction or expansion between the elements 1 and 3 would cause stresses to be set up within the heat exchanger. In this case the tubes 3 would bow or the welded joints between the flanges of the external 55 tube and the tube would give way, either of which is likely to cause damage to the structure.

As already pointed out, the described heat exchanger permits easy removal of the tube nest for cleaning. In practice, spare tube nests are kept on hand, and when it is necessary to dismantle the exchanger for cleaning, a spare nest is immediately inserted into the external tube, which procedure greatly reduces the time lost by shutting down.

It is to be understood that both ends of the heat exchanger may be provided with the flexible gasket herein described, which construction will give a greater amount of elasticity in relative expansion and contraction between the elements. 70

I claim:

1. A heat exchanger comprising a flanged tube of fairly large diameter having inlet and outlet ports in the walls thereof, a plurality of smaller tubes longitudinally disposed within said tube, tube sheets into which the ends of the smaller tubes are rolled, a flexible gasket detachably secured to, and of larger diameter than, one of the tube sheets, 80 flanged pipe fittings, means for securing the periphery of said gasket between the flange of one of the fittings and one of the flanges of the larger tube to seal the end of the larger tube, said gasket permitting relative expansion and contraction between the larger tube and the smaller tubes, said last named pipe fitting having abutments therein to limit the movement of the smaller tubes. 85

2. A heat exchanger comprising a flanged tube of relatively large diameter having inlet and outlet ports in the walls thereof, a plurality of smaller tubes longitudinally disposed within said tube, a tube sheet of the same diameter as the flanges of the larger tube, into which one end of each of the smaller tubes is rolled, a pipe fitting having a flange of the same diameter as the flanges of the larger tube, means for clamping the tube sheet between the flange of the fittings and a flange of the large tube, another tube sheet of smaller diameter than the inside of the larger tube, into which the other end of each of the smaller tubes is rolled, a flexible gasket of larger diameter than said last mentioned tube sheet and detachably secured thereto, a pipe fitting having a flange of the same diameter as the flanges of the larger tube, means for clamping the periphery of the gasket between the flange of the last mentioned pipe fitting and the other end of the larger tube to seal the end of the larger tube and permit relative expansion and contraction between the larger tube and the smaller tubes, said last mentioned pipe fitting having abutments therein to limit the movement of the smaller tubes. 100 105 110 115

In testimony of which invention, I have hereunto set my hand, at Philadelphia, Pennsylvania, on this 17th day of July, 1931.

VICTOR M. CHATFIELD.
